UNITED STATES PATENT OFFICE.

MICAJAH C. MALONE, OF PALMYRA, ILLINOIS, ASSIGNOR OF ONE-HALF TO
PAUL B. SPOONER, OF SAME PLACE.

COMBINED METAL-SHEARS AND TIRE-UPSETTER.

SPECIFICATION forming part of Letters Patent No. 411,386, dated September 17, 1889.

Application filed February 26, 1889. Serial No. 301,223. (No model.)

To all whom it may concern:

Be it known that I, MICAJAH C. MALONE, a citizen of the United States, residing at Palmyra, in the county of Macoupin and State 5 of Illinois, have invented new and useful Improvements in Combined Metal-Shears and Tire-Upsetters, of which the following is a specification.

My invention relates to improvements in 10 combined metal-shears and tire-upsetters; and it consists in certain novel features hereinafter described and claimed. In the accompanying drawings, Figure 1 is a perspective view of my improved device, and Fig. 2 15 is a side view.

Referring to the drawings by letter, A designates the lower or stationary jaw of the shears provided with a downward extension B, through which the securing-bolts are passed 20 into the work-bench to secure the device in position, and having on its upper side at one end the curved standard C, which is provided on its outer side with the transverse cogs or rack-teeth D, as shown. At the end of the 25 stationary jaw, opposite that end at which the standard C is erected, I pivot the upper or swinging jaw E. This jaw E is provided at its outer end with the bifurcation or fork F, which passes around the standard C, and the 30 operating-lever G is pivoted between the ends of this fork or bifurcation. The inner end of the operating-lever is provided with a segmental rack-bar H, which engages the teeth of the standard C, so that when the said lever 35 is vibrated it will be caused to move up or down on the said standard and to raise or lower the swinging jaw. The jaws A E are provided in their adjacent edges with the longitudinal recesses I, and the knives J are 40 secured in said recesses.

The jaw A is provided in its outer side with a recess K, which forms a continuation of a similar recess or groove L in the extension B, and the said jaw and extension are provided 45 with the outwardly-projecting rib M along one side of said recess. The upper jaw is provided with an offset N, which is adapted when the jaws are brought together to lie directly over the recess K, and is provided at 50 its edge with the lateral projecting rib or

plate O, forming practically a continuation of the rib N. In the upper end of the offset K and the lower end of the extension B, I secure the plates P, which are provided with teeth Q in their outer faces, and directly over said 55 plates I pivot to the ribs M and O the cam-levers R, which are provided in their inner edges with the transverse teeth S, as shown.

From the foregoing description the operation and advantages of my device will be apparent. When it is desired to divide a bar 60 of iron or other metal, the bar is inserted between the jaws and the operating-lever then lowered, thus bringing the upper jaw down upon the bar with a positive and strong pressure, so as to sever the same. When it is desired to upset a tire, the tire is clamped in 65 the recesses K and L and against the offset N by the cam-levers R being turned so as to cause the teeth S to bite against the tire and so secure it in position to be operated upon. The superfluous length of tire can then be 70 readily shrunk to make the tire fit tightly around the wheel.

My device is very compact in its arrangement, and by its use I am enabled to cut 75 heavy metal bars with very little labor, as the construction of the standard and the operating-lever moving thereon cause the upper jaw to exert a very powerful pressure against the lower jaw. The knives are removable secured to the jaw, so that they can be easily detached to be sharpened.

When it is desired to cut a tire or band, the operating-lever G and swinging jaw E are 80 raised above the standard C, when the tire or band can be placed between the jaws A and E. Then by lowering the lever G said tire or band can be readily severed.

Having thus described my invention, what 85 I claim, and desire to secure by Letters Patent, is—

1. The combination of the stationary jaw having the standard C erected at one end and provided with the transverse teeth D, the 90 swinging jaw pivoted to the stationary jaw and having a bifurcation at its free end passing around the standard, and the operating-lever pivoted in said bifurcation and provided at its end with the segmental rack-bar 95

engaging the teeth on the standard, as set forth.

2. The combination of the stationary jaw having the downward extension B, the upper jaw pivoted to the stationary jaws and having an offset N, the ribs M O, secured to the extension B and the offset N, respectively, and the cam-levers pivoted on said ribs, as set forth.

10 3. The combination of the stationary jaw having the recess K, and the downward extension B, provided with the recess L, forming a continuation of the recess K, the upper jaw pivoted to the stationary jaw and having an offset N, the ribs M O, and the cam-levers pivoted to said ribs and having teeth in their edges, as set forth.

15 4. The combined shears and tire-upsetter comprising the stationary jaw, the standard C, 20 erected at one end of the same and having the

transverse teeth E, the extension B, depending from the stationary jaw, the moving jaw pivoted to the stationary jaw and having a bifurcation at its free end passing around the standard C, the lever pivoted in said bifurcation and having a segmental rack - bar engaging the teeth of the standard C, the offset N on the swinging jaw, the ribs M O on the extension B and the offset N, respectively, the plates P, secured in the ends of the said extension and 25 offset, and the cam-levers pivoted to the ribs above said plates, as set forth.

In testimony that I claim the foregoing as my own I have hereto affixed my signature in presence of two witnesses.

MICAJAH C. MALONE.
